UNITED STATES PATENT OFFICE.

EDWARD B. FEASTER, OF LOWELL, AND CECIL B. ALMY, OF MARBLEHEAD, MASSACHUSETTS, ASSIGNORS TO SACO-LOWELL SHOPS, OF NEWTON UPPER FALLS, MASSACHUSETTS, A CORPORATION OF MASSACHUSETTS.

SPINDLE.

Application filed August 7, 1926. Serial No. 127,928.

This invention relates to spindles of the type used in spinning and twisting frames and particularly to spindles of the type in which the spindle is provided with a ball 5 and socket bearing whose members are frictionally engaged by a spring under a substantial initial compression, and which spindle is stepped at its lower end in a bearing member carried by the spindle bolster which 10 is located in an oil well formed in the bolster housing.

The present invention has for its object to provide a simple and improved construction of spindle having the characteristics of 15 the spindle referred to and additional characteristics as will be described.

To this end, the spring is located in the bolster housing below the ball and socket member affixed to the spindle and is placed 20 under the desired or required initial compression by means of the co-operating bearing member, which latter is located near the open upper end of the bolster housing, and is maintained therein by a retaining member, 25 as will be described.

The ball and socket members are located within the bolster housing with the center of the ball member substantially in the center of the line of pull of the belt or band on the 30 whirl fast on the spindle.

These and other features of the invention will be pointed out in the claim at the end of this specification.

Fig. 1 is a perspective view of a spindle 35 constructed in accordance with this invention;

Fig. 2, a vertical cross-sectional view of the spindle shown in Fig. 1;

Figs. 3 and 4, details of the ball and socket 40 members shown in Fig. 2;

Fig. 5, a vertical cross-sectional view on a larger scale through the ball and socket bearing members of the bolster and the adjacent parts, and

Fig. 6, a bottom view of the bobbin shown in Fig. 2.

The construction shown comprises a housing which includes a base 2 adapted to rest on the spindle rail of a spinning or twisting frame and a tubular part 3 extending downward from said base and forming an oil well. A portion of this extension 3 is screw-threaded to receive a nut which clamps the base 2 on the spindle rail. The housing also

includes a tubular extension 4 which projects upwardly from the base 2 for a short distance and is substantially in alignment with the part 3. Formed in the sections 3 and 4 of the housing is a vertical bore or chamber and mounted in this chamber is a bolster 5 in which the spindle 6 is rotatably supported. The bolster is provided with two bearings for the blade, one consisting of a step 7 of bronze or other suitable metal which is secured in the lower end of the 55 bolster, while the other bearing surface supports the blade laterally and includes that portion of the bore of the bolster above the shoulder 8, Fig. 5. Between these two bearings the blade is unsupported, but the fact that these bearings are widely separated, one being near the bottom of the housing and the other near the top, contributes to smooth 60 operation of the blade.

A whirl is secured on the blade 6 and includes a sleeve portion 10 and a pulley 12 to receive the driving band or belt. Either a flat or grooved pulley may be used, depending upon the type of driving belt which is employed. This whirl usually is forced onto the spindle under heavy pressure so that it is frictionally secured to the spindle. 75

A ball and socket bearing is provided for the bolster and supports the bolster and the spindle blade for tipping movement about a 80 center located within the whirl and preferably in the line of the belt pull. The ball member 15 of this bearing is of approximately hemispherical shape, as best shown in Figs. 3 and 5, with the rounded end thereof 85 uppermost, and it has an annular bearing face 16 at its lower side, the plane of this face being approximately perpendicular to the axis of the blade 6. Preferably this

plane passes through or close to the center of the ball 15. This ball member fits snugly in a socket member 17 which is positioned just above the ball. A spring ring 18 fitting in a groove 19 formed in the upper end of the tubular extension 4 of the spindle housing bears 90 against the upper end of the socket 17. The flat bearing face 16 of the ball member 15 rests on the upper end of a sleeve 20 which is 95 slidable in the part 4, and a coiled spring 21 which is seated on an interior shoulder 22, Fig. 2, formed in the part 3 of the spindle housing, presses the sleeve 20 upwardly and holds the ball member 15 firmly in its socket 100 105

17. In the construction shown this spring supports the entire weight of the spindle and its load, and the spring therefore is compressed so that it exerts a considerable pressure, say, 25 or 30 pounds on the ball 15. The degree of pressure used will vary with the type of spindle, a heavy spindle requiring a greater pressure than that just mentioned since the spindle shown is of a light or medium weight type.

10 The spring 21 is held in its compressed condition by the spring ring 18 above described, this ring preventing the spring from forcing the sleeve 20, bolster 5 and socket 17 upwardly out of the bolster housing.

15 Assuming now that the spindle is running and carrying a thread body, the weight of which is unbalanced or eccentrically disposed, this factor, and possibly also the tension of the thread or yarn, tend to tip the spindle and thus to produce the chattering or vibration which is so objectionable in the common constructions. The reason for 20 this appears to be that any spindle, whether of the construction here shown or of the usual commercial constructions, is mounted to rotate about its geometrical axis; and when such a spindle carries an unbalanced load and is run at high speeds it then tends 25 to rotate, not about its geometrical axis, but about an axis passing through the center of gravity of the entire rotating mass. Consequently, when a spindle so loaded is started 30 from a condition of rest and its speed of rotation is gradually increased, the forces tending to produce a shift from the geometrical axis to the natural axis of rotation gradually increase. A conflict, therefore, 35 is set up between the forces tending to maintain or establish these two axes, and if the spindle is supported in fixed bearings it vibrates or chatters.

40 In the present arrangement such a tipping movement of the spindle in any direction results in tipping the bolster about the center of the ball member 15. Referring to Fig. 5 it will be seen that such a tipping movement will depress the sleeve slightly 45 against the tension of the spring 21. The spring, therefore, yieldingly resists this tipping movement and tends to operate through the sleeve 20 and the ball member 15 to restore the spindle blade to its original upright position.

45 While the spindle, therefore, can yield to forces tending to tip it, it does, nevertheless, oppose a resilient or elastic resistance to such forces.

50 It will thus be observed that when the spindle is in operation the blade 6 has, in addition to its rotative movement about its axis, a rotary or gyrating motion around an axis passing through the center of gravity 55 of the entire rotating mass and the center of

the ball member 15. The rate of gyration depends upon the forces tending to produce such movement. The amplitude of gyration is very small so that to the eye the spindle appears to be rotating on a stationary axis 70 and to be running perfectly steady. During this gyrating motion only a small part of the annular bearing face 16 (theoretically a point) is in contact with the upper end of the sleeve 20, and this point of contact 75 travels around on the upper end face of the sleeve as the blade gyrates.

It should also be noted that since the bearing face 16 on the ball 15 is closely adjacent to the center of the ball, and the plane of 80 this face intersects the axis of the spindle at or close to the center of the ball, the distance through which the force tending to tip the spindle must act, is very short and the leverage exerted by an unbalanced load on the spindle consequently is relatively great. A considerable tipping movement of the upper end of the spindle, therefore, produces only a very slight depression of the sleeve 20 and a correspondingly slight rocking movement of the ball in its socket. These factors are important in obtaining the desired results.

Any tendency of the belt pull to tip the 90 spindle is counteracted by the centering of the ball and socket bearing substantially in the line of belt pull, it being understood that the belt moves up and down slightly over the surface 12 so that the exact line of the belt pull is constantly shifting up and down 100 through a very short distance.

For the purpose of lubricating the bearing surfaces, the base 2 is provided with the usual oil spout 24, the upper end of this spout being closed by a hinged cover 25. 105 This oil spout connects with the oil well in the lower part 3 of the bolster housing. Slots 26 formed in the lower part of the bolster admit oil to the step bearing 7 and also to the lower part of the spindle. When 110 the spindle is running oil travels upwardly along the surface of the spindle, through the lateral bearing at the upper end of the bolster, into the pocket 27, Figs. 4 and 5, formed in the socket member 17. The lower or bearing face of this socket member is 115 grooved, as best shown at 28, Fig. 3, to allow the oil to flow downward over the ball surface of the member 15, one or more slots or grooves 29, Fig. 3, being formed in this member to allow the oil to pass downward onto the sleeve 20 and thence back to the oil well. These parts thus are kept supplied with oil so that they can move freely.

It should be noted that the whirl shown 125 is unique in construction, in that the sleeve portion 10 is separated from the pulley section of the whirl by a flat shoulder 30, Fig. 1, on which the lower end of the bobbin 31 rests. The bobbin has a somewhat 130

deeper cavity 32 in its lower end than usual, and it sets down over the entire sleeve 10, resting on the shoulder 30 at the junction of the sleeve with the pulley. Two lugs 33—
 5 33 are riveted to this shoulder and project upwardly therefrom, these lugs being arranged to enter slots 34—34 formed in the base of the bobbin to drive the bobbin positively with the spindle. This construction
 10 has the advantage of utilizing all the available space above the pulley and thus permitting the use of longer bobbins than otherwise would be possible.

We have definitely demonstrated that this
 15 spindle does operate satisfactorily under unbalanced loads, and while we have given above the reasons which we believe are responsible for this improved operation, it should be understood that the invention is
 20 not limited to the theory of operation above advanced, this theory being held since it is supported by the data at present available to us.

The improved results above described
 25 have, however, been definitely established.

The spindle structure is relatively simple, the parts can be manufactured economically, and due to the efficient lubrication and the nature of the construction, wear and depreciation are reduced to a minimum. The spring and the various bearing members can all be assembled in the housing from the upper end, and the assembling operations can be performed very quickly and economically.

35 In assembling the spindle, the spring 21 is first inserted into the bolster housing and seated on the shoulder 22. The sleeve 20 is then inserted and rests on the spring 21. The bolster 5 is now inserted until the ball member 15 rests on the sleeve 20. The socket member 17 is then inserted and pressure is applied to it by means of a suitable tool, not shown, until the upper edge of the socket member has been forced below the annular
 40 groove 19 on the inner surface of the bolster housing, so that the split spring ring 18 may be inserted into said groove, whereupon the pressure upon the socket member 17 is removed and the latter is forced by the
 45 spring 21 into engagement with the retaining ring 18, which renders the socket member 17 stationary and causes it to act as an abutment for the ball member 15 which is forced against the same by the spring 21.

50 It will thus be observed that the parts may be quickly and easily assembled in the bolster housing and readily removed therefrom for repairs or other purpose, for by removing the retaining member or spring 18, the other parts are free to be removed. It will also be observed that when the parts are in their operative position within the bolster housing, the spring 21 is under a substantial initial compression, which is sufficiently great to create sufficient friction be-

tween the ball and socket members of the bolster to restrain the latter from rotating when supporting a balanced load and to initially resist and substantially overcome gyroscopic motion of said bolster when carrying 70 an unbalanced load.

It is preferred to provide the member of the ball bearing which engages the retaining ring 18, with a beveled surface at its upper end, so that when subjected to the pressure 75 of the spring 21, the beveled surface will force the retaining ring 18 into its groove 19 and act to lock it therein against accidental displacement.

It is preferred to provide the socket member 17 with four grooves or passages 28 set 90° apart and to provide the ball member with three passages 29 set 120° apart so that opportunity is afforded for the passage of oil from the chamber 27 to the upper 85 surface of the ball member under all conditions of use.

While we have herein shown and described a preferred embodiment of our invention, it will be understood that the invention may be 90 embodied in other forms without departing from the spirit or scope thereof.

Having thus described our invention, what we desire to claim as new is:

In a spindle, in combination, a bolster 95 housing having a rail-engaging base, a tubular member extended upwardly from said base and open at its upper end, and a tubular member extended downward from said base and closed at its lower end to form an 100 oil well, a bolster for the spindle blade insertible into the housing through the upper tubular member thereof and suspended at its upper end and having its lower end extended into said oil well, a ball and socket bearing for said bolster having a member attached to the bolster, and a co-operating member insertible into the housing through the open upper end of the upper tubular member of said housing and movable lengthwise of the said upper tubular member, a sleeve 105 slidable within the upper tubular member of the housing and co-operating with the bearing member attached to the bolster, a spring located in said housing below said sleeve and co-operating with the latter, said spring being constructed and arranged to be placed under a substantial initial compression by movement of the ball and socket bearing members within and lengthwise of the upper tubular member of the housing, and means co-operating with the upper tubular member of the housing and with the upper member of the ball and socket bearing 110 to retain said spring in its initially compressed condition.

In testimony whereof, we have signed our names to this specification.

EDWARD B. FEASTER.
 CECIL B. ALMY.
